UNITED STATES PATENT OFFICE.

CHARLES E. EVITTS, OF POTTSVILLE, PENNSYLVANIA.

SCREW-PROPELLER.

1,158,909.

Specification of Letters Patent.

Patented Nov. 2, 1915.

Application filed March 6, 1915. Serial No. 12,615.

To all whom it may concern:

Be it known that I, CHARLES E. EVITTS, a citizen of the United States, residing at Pottsville, in the county of Schuylkill and State of Pennsylvania, have invented certain new and useful Improvements in Screw-Propellers, of which the following is a specification, reference being had to the accompanying drawings.

10 My invention relates to propellers, and particularly to screw propellers of the ordinary type used for propelling motor boats or other vessels, whether in air or water.

15 The primary object of my invention is the provision of a propeller having its blades so formed and curved as to obviate slippage and further acting to relatively project a column of water directly toward the rear of the propeller or exert a direct rearward thrust against the water or other fluid upon which the propeller acts without allowing the water to pass laterally or radially as it were, of the blades.

20 A further object of the invention is the provision of a propeller wherein the blades shall not only extend obliquely with relation to the axis of the propeller, but wherein the outer ends of the blades shall be gradually curved rearward, thus preventing slippage and also exerting a thrust toward a line forming an extension of the axis of the propeller.

25 My invention is illustrated in the accompanying drawings, wherein—

30 Figure 1 is a face view of a propeller constructed in accordance with my invention; Fig. 2 is a perspective view looking toward the side of the propeller; Fig. 3 is a diagram showing the manner in which the elliptical curve of the propeller is drafted.

35 Referring to these drawings, 2 designates the hub of a propeller and 3 the blades thereof. Each blade at its base extends as usual diagonally to the axis of the hub. The 40 outer end of each blade is wider than its base and each blade at its outer end edge is disposed at an obtuse angle to the axis of the propeller. Each side edge of the blade is

given an elliptical curve, as shown most clearly in Fig. 2, and therefore the blade 50 itself is curved rearward so that the outer end of the blade is not only twisted but rearwardly curved, these curves being a section of an ellipse. The side edges of each blade extend radially to the axis of the propeller.

55 The blade is laid out in the manner shown in Fig. 3 wherein *a* is a base line having a length proportionate to that of the blade and *b* is a pitch line equal to the pitch of the blade. These lines are divided into an equal number of parts by indices. The lines *c* and *d* are then drawn from the corresponding indices on the pitch line and base line, and the outer intersections of 65 these lines gives the required elliptical curvature for the blades.

60 It will be noted from Fig. 2 that the forward and rear outer corners of each blade, because of the curvature of the blade, are 70 disposed rearward of the forward and rear inner corners of the blade, where the blade joins the hub.

Propellers constructed in accordance with my invention prevent the water or other 75 fluid from slipping laterally along the blade of the propeller, and the thrust of the blade is always transmitted directly rearward toward a line forming a continuation of the axis of the propeller, thereby securing a 80 maximum of power from the propeller.

I claim:

85 A propeller having blades twisted with relation to the axis of the propeller, the side edges of the blades being radial to the axis of the propeller, each blade having a longitudinal curvature from its base to its extremity, said curvature being a quarter of an ellipse, the greatest curvature being adjacent the outer end of the blade. 90

In testimony whereof I hereunto affix my signature in the presence of two witnesses.

CHARLES E. EVITTS.
